(57) **CLAIM**

The ornamental design for an exoskeleton combo case, as
shown and described.

DESCRIPTION

FIG. 1 is a first front perspective view of the exoskeleton
combo case, showing the new design with a door thereof in a
closed position;

FIG. 2 is a second front perspective view of the exoskeleton
combo case, showing the new design with a door thereof in an
open position;

FIG. 3 is a bottom plan view of the exoskeleton combo case;

FIG. 4 is a top plan view of the exoskeleton combo case;

FIG. 5 is a left side elevation of the exoskeleton combo case;

FIG. 6 is a right side elevation of the exoskeleton combo case;

FIG. 7 is a front elevation of the exoskeleton combo case;

FIG. 8 is a rear elevation of the exoskeleton combo case; and,

FIG. 9 is a rear perspective view of the exoskeleton combo
case.

In FIGS. 2, 8 and 9, broken lines indicate optional clips on an
inner surface of the door of the exoskeleton combo case that
form no part of the claimed design.
